UNITED STATES PATENT OFFICE.

WALTHER NACKEN, OF GRUNA, NEAR CHEMNITZ, GERMANY.

MULTIPLE-WIRE-DRAWING MACHINE.

Application filed July 6, 1928, Serial No. 290,764, and in Germany August 6, 1927.

My invention relates to multiple wire drawing machines consisting of a plurality of consecutive individual drums and in which the wire is drawn off through an eye or roller 5 located above the center of the drum and passed on to the next drum.

In these machines, slipping of the wire on the various drums is avoided by providing on each drum a certain amount of wire and by 10 the fact that each drum while pulling the wire required by it from the preceding drum, pays out substantially the same amount of wire to the following drum. Any difference between the taken up and paid out wire of 15 each drum is balanced by an increase or a reduction of the store of wire upon the drum.

My invention consists of an improved multiple wire drawing machine of this kind.

The accompanying drawings illustrate 20 some embodiments of my invention, by way of example.

In the drawings illustrates—

Fig. 1, a front elevation of the general arrangement, the inclined drums being shown 25 vertically for the sake of simplicity,

Fig. 2, a side elevation of the machine with the drum in the correct inclined position,

Fig. 3, a front elevation of a modified construction of my machine, in which the starting and stopping of the drawing drum is effected mechanically by the strength of the operator,

Fig. 4, a cross-section along line A—B of Fig. 3,

Fig. 5, a similar cross-section to Fig. 4, but with the operating parts in different positions,

Fig. 6, a detail of Fig. 3 in plan,

Fig. 7, a front elevation of another modified 40 construction of my machine,

Fig. 8, a cross-section along line C—D of Fig. 7,

Fig. 9, a longitudinal section through the starting and stopping gear of the machine according to Fig. 7, with the drawing drums in 45 elevation,

Fig. 10, a plan of the stopping gear,

Fig. 11, a plan of the stopping and starting levers, and

Fig. 12, some details in sectional elevation.

Like parts are indicated by like letters of reference throughout the figures of the drawings.

The process of drawing the wire and the mode of operation of my improved machine 55 will be described first with reference to Figs. 1 and 2 of the drawings.

In the drawings is illustrated a machine with 4 draw dies, but it will be understood that the machine might have any suitable 60 greater number of these elements. 5, 6 and 7 are the preliminary drawing drums, while 8 is the drum for winding up the finished wire. The wire passes through the first draw die 1 on to the drum 5, is coiled around this drum 65 in a suitable number of turns, drawn off at the point of the drum, passed around a roller 9 at the top and then downwards to a roller 90 and to the next draw plate 2, the roller 90 being preferably submerged in a drawing 70 solution contained in a trough 12 arranged at the front of the machine. This process is repeated at the drums 6 and 7 and die 3, whereupon the finished wire after having passed through the eye 4 is wound upon the drum 8. 75

At the front of the machine, there is arranged at each drum a treadle or handle 14, 15, 16, 17. These levers act in a suitable manner, which will be described in detail later on, upon a clutch provided at each drum, 80 which is generally indicated at 18 in Fig. 2. The treadles are also connected with one another in a definite manner. While by the operation of the treadle 14 merely the drum 5 is thrown into or out of gear, the treadle 15 is coupled with the lever 14 in such a manner that it throws out and in not only the drum 6 but simultaneously the drum 5. The treadle 15 has, on the other hand, no effect upon the drums 7 and 8. The treadle 16 does 90 not only throw the drum 7 into and out of gear, but simultaneously also the drums 6 and 5. The treadle 17, on the other hand, throws not only the drum 8, but also all the drawing drums 95 on the left of it simultaneously out of or into gear.

This mechanism operates in the following manner: If a wire is to be drawn on the machine, it is by hand or by means of a suit- 100

able mechanical device threaded through the first die 1, so that it projects by about 20 to 30 inches. This die is then inserted into the holder of the machine, the drum 5 stopped by, 5 for instance, depressing the right-hand side footrest of the treadle 14, and the loose end of the wire slung around the drum and attached at the upper end of the drum in some suitable manner. The drum 5 is now started 10 by depressing the left-hand side footrest of the treadle 14, and the wire is slung in about 20 to 30 turns around the drum. Then the drum 6 as well as the drum 5 are stopped by the treadle 15. The operator detaches the 15 wire from the point of the drum 5 and pulls the end across the roller 90 to the next die 2. This die is slipped over the wire, placed into its holder and the end of the wire attached to the second drum 6. By means of the treadle 20 15, the drum 6 as well as the drum 5 is now simultaneously started, and while the drum 6 pulls its wire from the drum 5, the drum 5 takes up its wire by pulling it through the die 1. When the second drum 6 has taken 25 up sufficient wire, both drums are arrested by means of the treadle 15. If the treadle 15 would act on the drum 6 only, the drum 5 would continue to revolve and twist the wire off at the point of the drum. All three drums 30 7, 6 and 5 might, of course, be stopped simultaneously, in order to tie the wire directly to the drum 7 after passing it through the second die 3, whereupon all three drums 7, 6 and 5 are then rendered operative by means of the 35 treadle 16. When the finished wire is finally tied to the drum 8, the entire machine is started by depressing the treadle 17, and the wire is drawn through the machine. When the drum 5 is again becoming empty, the 40 operator stops this drum by means of the treadle 14 and threads the end of a fresh coil of wire through the first die and on to the first drum without interfering with the run of the remaining drums. When the second drum 45 has become empty, the just described process is repeated. It will be understood that it is thus unnecessary to stop the entire machine whenever a fresh wire is to be drawn in and that the next coil of wire may be drawn into 50 the machine as soon as a coil of wire has left the first drum, while the remaining drums continue to revolve.

The throwing into and out of gear of the drums may be effected in any suitable manner, for instance electrically. For this purpose, solenoids of known or suitable kind may be connected into a suitable electrical circuit by depressing selectively the treadles 14 to 17, respectively, said solenoids throwing 55 clutches of the drums in known or suitable manner electrically or mechanically out or into gear and being electrically connected with one another in such a way that when one of the pedals is depressed the solenoid co-ordinated to it as well as the solenoids of the

drums on the left of it are simultaneously connected or disconnected to throw out of gear or into gear the electric or mechanical clutches of the respective drums. It will be readily understood that push buttons or other suitable means may be employed instead of the treadles for controlling the solenoids or other suitable electrical devices. 70

This electromagnetic clutch engaging and disengaging gear is particularly suitable in 75 cases in which the attendant is not able to operate the clutches by hand, for instance when stout wire is drawn and the clutches become very heavy. In such a case, the arrangement may also be such that a purely 80 mechanical arrangement is provided, which the attendant operates by the aid of an appropriate auxiliary clutch of any known or suitable construction which he can throw into or out of gear easily by means of a treadle 85 or handle and which in its turn is driven by the machine or by any other force. This auxiliary clutch in its turn then throws the main clutches of the drums into or out of gear, so that the workman himself has not 90 to overcome the resistance of the main clutches at the various drums, but that this is effected by the easily operated auxiliary clutch.

The auxiliary clutch is preferably so arranged, that the treadles 30 mentioned in conjunction with the following description of the design of the machine illustrated in Figs. 3 to 6 serve to throw the auxiliary clutch out and into engagement, while the hereafter mentioned treadles 14, 15, 16, 17 serve as control members, so to say, by means of which the clutch may be thrown into gear with the respective drums, so that the engagement and disengagement of the drums belonging to the treadle as well as the preceding drums takes 105 place in common. 95

In the Figs. 3 to 6, there is illustrated a relatively light machine in which the attendant effects the engagement and disengagement of the drums mechanically by his strength only without driven auxiliary clutch. The treadles 15^a, 16^a and 17^a are at their left-hand end provided with a suitable extension 29^a, 29^b, 29^c, which projects beyond the preceding treadle, so that by depressing a treadle 110 all the treadles on the left of it are also depressed, while the treadles on the right are not affected. At the front of the machine above the treadles is turnably mounted in bearings of the end frames a rod 18. On this rod there are mounted levers 19^a, 19^b, 19^c, 19^d hanging downwards. On these levers are pivoted the pawls 20^a, 20^b, 20^c, 20^d in such a manner that when depressing one of the treadles 14^a, 15^a and so on, the respective pawl provided at the 115 inner end with a counterweight is moved by the respective treadle out of the way and drops to the front again and arrests the depressed treadle in its lowest position, as will be clearly seen in Fig. 5. By depressing the 120

treadles 14^a or 15^a and so on against the resistance of the springs 91, the drums 5, 6, 7 and so on are lifted by a pushrod 21 provided under each drum spindle 22 and thereby their 5 lower clutch discs 23 are detached from the cooperating clutch discs 24 which are continuously rotated from the driving shaft 25 by means of the pairs of bevel wheels 26, 27. On a separate rotatably mounted shaft 28, 10 there are mounted further auxiliary treadles 30^a, 30^b, 30^c, 30^d. On said shaft 28, there is further mounted a lever 31, which acts on a lever 34 by means of a pushrod 32 and spring 33, said lever being fixed on the shaft 18. 15 The mode of operation of this embodiment of my improved drawing machine is as follows:

Assuming that the last end of a coil of wire has left the drum 5, so that this drum is empty, all the drums revolving and the treadles 14^a, 20 15^a, 16^a, 17^a being in their raised position. By depressing the treadle 14^a at the point marked with "E" in Fig. 6, the drum 5 is uncoupled and stops. The treadle 14^a merely forces the movable pawl 20^a downwards with- 25 out moving the lever 19^a. When the treadle has reached its lowest position according to Fig. 5, the pawl 20^a drops to the front again and prevents the treadle 14^a from ascending, so that the drum 5 is held in the inoperative 30 state, as already described above, the first die into which the beginning of the new wire coil has already been threaded before is then placed into the die holder of the drum 5, and the end of the wire fixed to the drum. To 35 start the drum 5 again, the operator steps with his foot on the spot of the treadle 14^a designated with "F" in Fig. 6. He thus depresses firstly the treadle 30^a and puts the spring 33 under tension by means of the lever 31 and the 40 rod 32 and thereby also sets under spring tension the levers 19^a, 19^b, 19^c, 19^d on the shaft 18 by means of the lever 34 and the said shaft. The levers are, however, not able to follow this tension, because they are for the time being held in their position due to the frictional 45 resistance between the pawl 20^a and the treadle 14^a. During the depression of the treadle 30^a the tension of the spring 33 increases until the treadle 30^a has been lowered 50 to the level of the treadle 14^a in Fig. 5. If, then, the treadle 30^a be further depressed, the operator's foot encounters the treadle 14^a and depresses the same. As a result, the frictional resistance between the pawl 20^a and 55 the treadle 14^a is eliminated and levers 19^a, 19^b and so on are now able to follow the pull of the spring 33, move inwards and give the way free for the ascent of the treadle 14^a, so that the drum 5 is started again and commences to 60 draw wire. Meanwhile the wire has also left the drum 6. By depressing the treadle 15^a, the treadle 14^a simultaneously descends, both pawls 20^b and 20^a being deflected inwards when the treadle sweeps past and then keep 65 the treadles in the depressed position by tum-

bling towards the front again. The operator now detaches the end of the wire from the drum 5 in the manner described before and fixes the end of the wire drawn through the second die to the drum 6. When starting the 70 drum 6, the operator again depresses the auxiliary treadle 30^b and thus sets the spring 33 under tension, without the levers 19^a, 19^b being able to follow the pull, because they are maintained in their position by the frictional 75 resistance of the pawls 20^a and 20^b on the main treadles 14^a and 15^a. Only when the lever 15^a and thus by the overlap 29^b the treadle 14^a has been depressed by a certain distance and the pawls 20^b and 20^a have become free, 80 the levers 19^a and 19^b are able to follow the pull of the spring 33 and to deviate inwards, so that the treadles 14^a and 15^a are able to ascend and to render the drums 5 and 6 operative. 85

The process with regard to the third drum 7 and any other following drums is similar to the above described.

From the above it will be obvious that by throwing into or out of gear one of the drawing drums not only all the preceding drawing drums are likewise thrown out and in, but that one drawing drum and thus all the preceding drawing drums can only be thrown 90 into gear, if the following drums are running 95 viz, are thrown into gear. This advantage is of great importance, because otherwise it might happen that when one drum runs, while the following stops, the wire passed over the point of the rotating drum on to the 100 stationary drum would be twisted and break. On the other hand, it would of course be possible to stop the drums on the left, while those on the right continue to revolve, and this 105 fact is of great importance, because when in the case of big wire coils one or the other drum would become filled up excessively, it is possible to arrest this drum temporarily and thus to reduce the store of wire on this 110 drum.

In the Figures 7 to 12 is illustrated one of the above mentioned heavy duty machines for which the bodily strength of the attendant would not suffice for the mechanical disengagement of the individual clutches. Instead 115 of employing for this purpose the above mentioned special auxiliary clutch, the mechanical starting and stopping of the drums is here effected in the following manner:

Each drum is again provided with a clutch 120 of any suitable kind, which in Fig. 8 as in the design according to Figs. 3 to 6 is shown as a cone clutch 23, 24, so that in the present case also the engagement or disengagement of the 125 clutches may be effected by raising or lowering the drum spindles 22. Below the main shaft 25 is mounted in the machine framing a second shaft 36 and upon this latter shaft are guided displaceable sliding members, for instance bushes 37^a, 37^b, 37^c, 37^d, as well as 130

intermediate members such as bushes 38^a, 38^b, 38^c. The sliding bushes carry upon their upper side cams or tappets 39^a, 39^b, 39^c, 39^d upon which rest push rods 21^a, 21^b, 21^c, 21^d by 5 means of antifriction rolls 40^a, 40^b, 40^c, 40^d. By reciprocating the said slide bushes, the clutches of the drums 5, 6, 7 and 8 may thus be disengaged or engaged. The intermediate bushes 38^a, 38^b, 38^c serve to maintain accurate 10 spacing between the main bushes, so that by displacing for instance the first slide bush 37^a towards the right, all the drums are started, while by moving the slide bush 37^a towards the left all drums are simultaneously 15 lifted and thus thrown out of gear. If on the other hand the central slide bushes are moved towards the right or the left, only the drums located at the right or left therefrom are affected thereby. 20 Behind the stationary shaft 36, there is journaled a slideable shaft 40, which has a continuous reciprocating motion imparted to it either from the main shaft 25 by a transmission gear of known or suitable design or by 25 some other machine power, for instance by a crank mechanism, which is diagrammatically indicated at 50, 51. Upon said shaft 40 are mounted rotatably, but secured against lateral motion by collars, fork-shaped rotary 30 members 41^a, 41^b, 41^c, 41^d, 41^e. The members 41^b to 41^e are adapted to be turned by depressing the treadles 14^b, 15^b, 16^b, 17^b in such a manner that, for example by means of inner limbs 52^b, 52^c, 52^d and 52^e, they come into engagement 35 with lateral extensions 60^a, 60^b, 60^c and 60^d of the slide bushes and thus move them them towards one side by the aid of the displacement of the rod 40 effected by the above mentioned crank gearing. The design is 40 such that the slide bushes are movable by the rotary parts 41^b, 41^c, 41^d and 41^e to the left only. For this purpose, the extensions 60^a, 60^b and so on of the slide bushes are so long that the limb or nose 52^b etc. of the rotary part 45 41^b etc. with depressed treadle only engages the rear of this extension when the shaft 40 is in its extreme right-hand position, and during the next displacement of the shaft 40 said engaging part will then move the coordinated 50 slide member towards the left as well as by means of the bushes 38^a etc. all the slide bushes at the left and thus will throw out of gear the drum belonging to it as well as all the drums on the left of it, while the drums 55 on the right remain unaffected. The treadle 14^b, 15^b, 16^b or 17^b appertaining to each drum is individually rotatably mounted on a likewise rotatably journaled shaft 43. Upon this shaft 43, there are, moreover, fixed 60 treadles 14^c, 15^c, 16^c, 17^c belonging to each drum, so that by depressing any one of these treadles, the entire shaft 43 is turned, while this is not the case on depressing the rotatably journaled treadles 14^b, 15^b, 16^b, 17^b. At 65 the left-hand end of the shaft 43, there is

fixed an arm 44, as shown in Fig. 12, which engages the rotary part 41^a of the shaft 40 and by depressing one of the treadles 14^c, 15^c, 16^c or 17^c said arm moves said part 41^a into engagement with the left end of the extension 60^a of the slide bush 37^a, in such a manner that during the next displacement of the shaft 40 towards the right, the part 41^a will move this bush and thereby all the intermediate bushes and main slide bushes, as far as they 70 occupy their left position, towards the right. 75

By depressing one of the treadles 14^b, 15^b, 16^b, 17^b, the coordinated drum and the drums on the left of it are thus always thrown out of gear. By depressing one of the treadles 80 14^c, 15^c, 16^c or 17^c, on the other hand, all the drums, as far as they are not already thrown into gear, are started.

The above described designs or embodiments of my invention are to be understood 85 as examples only and should of course not be considered as limitations. It is obviously immaterial whether the drums are located at an angle to the horizontal, as shown in Fig. 2, or whether they stand at right angles to it, 90 as illustrated in the other figures of the drawings. This will mainly depend upon the demands which the wire to be drawn makes on the drawing machine or bench.

Various modifications and changes may be 95 made without departing from the spirit and the scope of the invention, and I desire, therefore, that only such limitations shall be placed thereon as are imposed by the prior art. 100

I claim as my invention:—

1. In a multiple wire drawing machine with a plurality of consecutive drawing drums each provided with means permitting the wire to uncoil as well as unwind, in combination, mechanism for driving said drums, means for coupling and uncoupling each drum individually with said driving mechanism, and means for each drum for throwing said coupling means into or out of gear and adapted to throw the preceding drums simultaneously into or out of gear, while leaving the following drums unaffected. 105 110

2. In a multiple wire drawing machine with a plurality of consecutive drawing drums each provided with means permitting the wire to uncoil as well as unwind, in combination, mechanism for driving said drums, means for coupling and uncoupling each drum individually with said driving mechanism, and means for each drum for throwing said coupling means into or out of gear, said means standing in such relation to one another that by the operation of the throwing out means of one drum the like means of the preceding drums are operated in the same way, while the like means of the following drums remain unaffected. 115 120 125

3. In a multiple wire drawing machine with a plurality of consecutive drawing 130

drums each provided with means permitting the wire to uncoil as well as unwind, in combination, mechanism for driving said drums, means for coupling and uncoupling each drum individually with said driving mechanism, mechanically operated means for each drum to throw said coupling means into and out of gear, and means for each drum for controlling said mechanically operated means, said 5 throwing out means standing in such a relation to one another that by the operation of the throwing out means of one of said drums the like means of the preceding drums are operated in like manner, while the like means 10 of the following drums remain unaffected.

4. In a multiple wire drawing machine with a plurality of consecutive drawing drums each provided with means permitting the wire to uncoil as well as unwind, in combination, mechanism for driving said drums, each of said drums being adapted to be raised and lowered, a coupling member on each drum adapted to be thrown out of and into engagement with a corresponding coupling 20 member driven by said driving mechanism by raising and lowering said drum, means for raising and lowering each drum, and means at each drum to throw said raising and lowering means into and out of gear, said 25 means standing in such relation to one another that by the operation of said means of one drum the like means of the preceding drums are operated in like manner, while the like means of the following drums remain unaffected.

5. In a multiple drawing machine with a plurality of consecutive drawing drums each provided with means permitting the wire to uncoil as well as unwind, in combination, mechanism for driving said drums, each of said drums being vertically slidably guided by a central spindle and provided at its lower end with a coupling disc, means for each drum for throwing the coupling disc out 40 of or into engagement with the cooperating driving coupling disc by raising and lowering said central spindle, said means standing in such relation to one another that by the operation of the means of one drum the like means of the preceding drums are operated in like manner, while the like means of the following drums remain unaffected.

6. In a multiple wire drawing machine with a plurality of consecutive drawing 55 drums each provided with means permitting the wire to uncoil as well as unwind, in combination, mechanism for driving said drums, means for coupling and uncoupling each drum individually with said driving mechanism, and means for each drum for throwing said coupling means into or out of gear, said means consisting of a number corresponding with the number of drums of slideable main members and also slidable auxiliary members, said auxiliary members being arranged 60

intermediately said slideable main members in such relation that when one of said main sliding members is displaced in the direction of disengagement, by means of said intermediate members the slideable members of 70 the preceding drums are displaced in the same direction, while the slideable members of the following drums remain unaffected

7. In a multiple drawing machine with a plurality of consecutive drawing drums each 75 provided with means permitting the wire to uncoil as well as unwind, in combination, mechanism for driving said drums, each of said drums being adapted to be raised and lowered, a coupling member on each drum 80 adapted to be thrown out of and into engagement with a corresponding coupling member driven by said driving mechanism by raising and lowering said drums, means for raising and lowering each drum, said means 85 comprising a number corresponding with the number of drums of sliding bushes with lifting cams longitudinally slideable upon a rod, said cams being adapted to lift the respective drums when displacing said sliding 90 bushes in one direction and permit the lowering of the drums when displacing said bushes in the opposite direction, and also intermediate bushes longitudinally displaceable on said rod, which are located between the said 95 first sliding bushes in such a manner that when a sliding member is displaced in the direction of disengagement, by means of the said intermediate members the sliding members of the preceding drums are displaced in 100 the same direction, while the sliding members of the following drums are not displaced.

8. In a multiple wire drawing machine with a plurality of consecutive drawing drums each provided with means permitting the wire 105 to uncoil as well as unwind, in combination, mechanism for driving said drums, means for coupling and uncoupling each drum with said driving mechanism, and means for each drum for throwing said coupling means into or 110 out of gear, said means comprising a number corresponding with the number of drums of displaceable sliding members and of likewise displaceable intermediate members located between the said slideable members in 115 such a relation that on displacement of one of the sliding members in the direction of disengagement, by means of the said intermediate members the slideable members of the preceding drums are displaced in the same 120 direction, while the slideable members of the following drums are not displaced, means for displacing the slideable members in the direction of disengagement consisting of a corresponding number of entraining members, means for mechanically reciprocating said latter means continuously, and means for throwing any desired entraining number selectively into or out of operative engagement 125 with the respective sliding member by means 130

of the disengagement member of the respective drum.

9. In a multiple wire drawing machine with a plurality of consecutive drawing drums each provided with means permitting the wire to uncoil as well as unwind, in combination, mechanism for driving said drums, means for coupling and uncoupling each drum with said driving mechanism, and means for each drum for throwing said coupling means into or out of gear, said means comprising a number corresponding with the number of drums of displaceable sliding members and of likewise displaceable intermediate members located between the said slideable members in such a relation that on displacement of one of the sliding members in the direction of disengagement of one of the sliding members by means of the said intermediate members the slideable members of the preceding drums are displaced in the same direction, while the slideable members of the following drums are not displaced, means for displacing the slideable members in the direction of disengagement consisting of a corresponding number of sleeves mounted upon a mechanically and continuously reciprocated rod so as to be rotatable, but not slideable thereon, and adapted to be turned into operative engagement with a stop of the respective slideable member by means of the respective disengagement members of the drums and independent of one another.
10. In a multiple wire drawing machine with a plurality of consecutive drawing drums each provided with means permitting the wire to uncoil as well as unwind, in combination, mechanism for driving said drums, means for coupling and uncoupling each drum with said driving mechanism, and means for each drum for throwing said coupling means into and out of gear, said means consisting of a number corresponding with the number of drums of slideable members and also slideable intermediate members arranged between said slideable main members in such relation that when one of said sliding members is displaced in the direction of disengagement, by means of said intermediate members the slideable members of the preceding drums are displaced in the same direction, while the slideable members of the following drums remain unaffected, mechanically reciprocated entraining members adapted to be brought selectively in engagement with the coordinated slideable members and to move the said slideable members into the operative position, means for returning said slideable members into the inoperative position consisting of an entraining member common to all of said slideable members, means for mechanically reciprocating said entraining member, and means for throwing said entraining member into and out of operative engagement with said slideable member of

the first drum, said last means consisting of a member adapted to be operated by the engagement member of each drum.

11. In a multiple wire drawing machine with a plurality of consecutive drawing drums each provided with means permitting the wire to uncoil as well as unwind, in combination, a mechanism for driving said drums, means for coupling and uncoupling each drum with said driving mechanism, means for each drum for throwing said coupling means into and out of engagement, said means consisting of a number corresponding with the number of drums of slideable members and of likewise movable intermediate members located between said slideable members in such a relation that when one of said slideable members is moved in the direction of disengagement, by means of said intermediate members the slideable members of the preceding drums are displaced in the same direction while the slideable members of the following drums are not displaced, means for displacing the slideable members into their operative position consisting of sleeves mounted rotatably but not slideably upon a rod mechanically continuously reciprocated and adapted to be turned into operative engagement with the corresponding slideable member by means of the respective disengagement members of the drums independent of one another, means for the return of the slideable members in their inoperative position consisting of a common entraining member mounted on said mechanically reciprocated rod rotatably but not slideably, and means for throwing said entraining member into and out of operative engagement with the first slideable member by each of the engagement members provided for said drums.

In testimony whereof I have affixed my signature.

WALTHER NACKEN.
